(57) **CLAIM**

The ornamental design for a large identification tag for a fitness device, as shown and described.

DESCRIPTION

FIG. 1 is a perspective view of the large identification tag for a fitness device in accordance with my design;

FIG. 2 is left side view thereof;

FIG. 3 is a right side view thereof;

FIG. 4 is a top view thereof;

FIG. 5 is a bottom view thereof;

FIG. 6 is a right end view thereof; and,

FIG. 7 is a left end view thereof.

The broken lines illustrate portions of the environment in which the identification tag is used which form no part of the claimed design.
